UNITED STATES PATENT OFFICE

ALEXANDER FISHER, OF CHICAGO, ILLINOIS

DESIGN FOR A COMBINATION TAIL AND STOP LIGHT

Application filed August 25, 1930. Serial No. 36,757. Term of patent 3½ years.

To all whom it may concern:

Be it known that I, ALEXANDER FISHER, a citizen of the United States, residing at Chicago, in the county of Cook and State of Illinois, have invented a new, original, and ornamental Design for Combination Tail and Stop Light, of which the following is a specification, reference being had to the accompanying drawing, forming part thereof.

Fig. 1 is a front elevation of the combination tail and stop light showing my new design, in which the skull and cross bones are

used for the red stop signal and the triangular window in the lower portion of the device is used only for the red tail light.

Fig. 2 is a side elevation of the device shown in Fig. 1, and

Fig. 3 is a bottom view of the device showing the bottom white window for illuminating license plate.

I claim:

The ornamental design for a combination tail and stop light as shown and described.

ALEXANDER FISHER.
